UNITED STATES PATENT OFFICE

2,620,606

PORTABLE JOINTER KNIFE GRINDER

Edwin A. Dvorak, Edgerton, Wis.

Application January 11, 1951, Serial No. 205,571

1 Claim. (Cl. 51—249)

1

This invention relates to an apparatus designed primarily for grinding the knives or blades of wood jointers, eliminating the necessity of removing the knives from the machine to grind or sharpen the knives.

An important object of the invention is to provide a portable jointer knife grinder which may be clamped in position against the knives, the sharpener being movable longitudinally of the blades for sharpening the blades throughout their entire lengths.

Another object of the invention is to provide means whereby the grinding wheel may be adjusted with respect to the blades being ground, to insure the true grinding of the blades.

With the foregoing and other objects in view which will appear as the description proceeds, the invention consists of certain novel details of construction and combinations of parts herein-after more fully described and pointed out in the claim, it being understood that changes may be made in the construction and arrangement of parts without departing from the spirit of the invention as claimed.

Referring to the drawings,

Figure 1 is a side elevational view, illustrating a portable grinding device constructed in accordance with the invention, as mounted on the table of the jointer or planing machine.

Fig. 2 is a front elevational view thereof.

Fig. 3 is a plan view illustrating the grinder attachment as mounted on the jointer.

Fig. 4 is a fragmental perspective view illustrating the grinding device as mounted for grinding a blade of the jointer.

Fig. 5 is a sectional view taken substantially on line 5—5 of Fig. 2.

Referring to the drawings in detail, the reference character 5 indicates the jointer table which is provided with an opening through which the blades 6 of the rotary cutter 7, extend for planing lengths of wood moved over the table.

The rotary cutter is mounted on the shaft 8 and is operated in the usual and well known manner.

The device forming the subject matter of the present invention, embodies a supporting rod 9 which has its ends mounted in the brackets 10 that extend forwardly from the bar 11. Secured to the bar 11 and depending therefrom, is the stop 12 which is adapted to be positioned against one side of the jointer table, the stop 12 cooperating with the head 13 mounted on the inner end of the threaded shank 14 that moves through the threaded bore formed in the lug 55

2

15. The handle 16 affords means whereby the threaded shank may be rotated to move the head 13 into clamping relation with the side of the jointer table, as clearly shown by Fig. 2 of the drawings.

The reference character 17 indicates the supporting plate of the portable grinding device, to which the plate 18 is secured as by welding, the plate 18 being disposed at an oblique angle with respect to the supporting plate 17, as shown by Fig. 5 of the drawings. This plate 18 is provided with an elongated opening 19 through which the lug 20 extends, the elongated opening providing a guide for the lug, to insure true movement of the adjustable support 21 that is provided with a bearing opening in which the shaft 22 operates, the shaft 22 providing a support for the grinding stone 23, the shaft 22 being rotated by a suitable power means indicated by the character A which may be a suitable power tool. As shown by Fig. 5 of the drawings, one end of the plate 18 extends at right angles as at 24, the right angled end of the plate 18 being formed with an opening, through which the shaft 25 extends, the shaft 25 being provided with the collar 26 for restricting movement of the shaft 25 through the opening.

The knob 27 is secured to the shaft 25 and contacts the outer surface of the right angled end 24 of the plate 18, so that the right angled end is clamped between the collar 26 and knob 27. The threaded portion of the shaft 25 extends into the threaded bore 28 of the adjustable support 21, and by rotating the shaft 25, the threaded portion of the shaft will operate to move the adjustable support 21 longitudinally of the plate 18. A set screw 29 extends through a threaded bore in the lug 20, and contacts with the plate 18, adjacent to the elongated opening 19, securing the adjustable support 21, in various positions of adjustment along the plate 18.

As shown, the adjustable support 21 may be moved to extend the grinding stone 23 to the desired position for grinding the knives of the jointer.

The plate 18 is provided with a cut out portion 30 in which the grinding stone 23 operates, the plate 18 being of a length to engage against one side of the blade being sharpened to hold the grinding stone in its proper position.

Mounted on the supporting plate 17, is the handle 31 by means of which the supporting plate 17 may be moved longitudinally of the supporting rod 9, thereby moving the grinding stone 23 into engagement with the knife or cutting blade

being sharpened, throughout the entire length of the knife or cutting blade.

In order that the rotary cutter 7 will be held against rotation during the sharpening of the knives or blades carried thereby, the rod 32 is provided, which rod is provided with a hook 33 at its free end, the hook being designed to hook behind a blade 6 of the rotary cutter being sharpened, the opposite end of the rod 32 passing through an opening in the flange 34 of the bar 11, where it is connected with the coiled spring 35 which spring is anchored to the bar 11, at 36. Thus it will be seen that due to this construction, as the grinding stone is being rotated to grind or sharpen a knife or blade of the rotary cutter, the rotary cutter will be held stationary against the rotary action of the grinding stone. While the rod 32 provides means for securing the rotary cutter against rotation while being sharpened, it will be readily seen that the rod may be readily and easily positioned for holding the rotary cutter, or the rod may be removed to release the cutter blades and allow the jointer to operate in the usual manner.

Having thus described the invention what is claimed is:

A portable grinding device for grinding the blades of a jointer having a table, comprising a supporting bar, clamping means for clamping the supporting bar to the table, brackets extending forwardly from said supporting bar, a supporting rod mounted in the brackets and disposed transversely of said table, a supporting plate slidably mounted on said rod at one end of the supporting plate, a plate secured to the forward end of the supporting plate inclined with respect to the sup-

porting plate, the latter plate having a cut-out portion extending inwardly from the forward edge thereof, the forward edge of said latter plate being engageable with the side edge of the 15 jointer blade being sharpened to hold the latter plate against movement in one direction, a grinding stone adjustably mounted on said latter plate and operating through said cut-out portion to grind the jointer blade disposed thereunder, a handle rising from said supporting plate effecting movement of said supporting plate and grinding stone transversely of the table and jointer blade being sharpened, and a rod secured at one of its ends to said supporting bar, said rod having a hook at one end thereof adapted to hook over the blade being sharpened to hold the blade in engagement with said latter plate.
